UNITED STATES PATENT OFFICE.

HEZEKIAH PHILIP FLICKINGER, OF SPOKANE, WASHINGTON.

HEAT RADIATOR.

Application filed August 8, 1923. Serial No. 356,325.

To all whom it may concern:

Be it known that I, HEZEKIAH PHILIP FLICKINGER, a citizen of the United States, residing at Spokane, in Spokane County, and 5 State of Washington, have invented certain new and useful Improvements in Heat Radiators, of which the following is a specification.

My present invention relates to improvements in heat radiators of the type utilizing 10 electrical energy for producing hot water within the radiator, and especially adapted for domestic use. The primary object of the invention is the provision of a portable 15 or interchangeable electric heating device or electric heater which may when desired be conveniently and with facility attached to and detached from a hot water or similar heat-radiator of standard type and construction. The invention may be adapted for use 20 as an auxiliary heater in existing hot water heating systems when heat is desired from a single unit of the system. Or a number of 25 single and independent radiators may each be equipped with one of my electrical heating appliances for the purpose of heating the several rooms of a dwelling.

The invention consists in certain combinations and arrangements of parts involving 30 a portable heating element and a water tank forming part of the radiator to which the element is applied whereby the heating device may quickly and conveniently be put into use, as will be described. In the accompanying drawings I have illustrated one 35 complete example of the physical embodiment of my invention wherein the parts are combined and arranged according to the best mode I have so far devised for the practical 40 application of the principles of my invention.

Figure 1 is a view in side elevation showing 45 a hot water heat radiator of standard type equipped with the electrical heating device of my invention.

Figure 2 is an end view of the radiator so equipped.

Figure 3 is a perspective view of the water heating tank, detached from the radiator.

Figure 4 is a longitudinal, vertical sectional view of the water-heating tank.

Figure 5 is a perspective view of the electric heating element for use with the water-heating tank.

In Figs. 1 and 2 of the drawings I have

illustrated a well known type of heat-radiator 1 made up of water tubes or pipes and equipped with an indicator 2, a filling cap for the radiator being indicated at 1^a. 60 The radiator is preferably elevated, as usual, above the floor and supported on legs 3, to provide sufficient or adequate space beneath the radiator and on the floor, for a water-heating tank 4. The tank is of ample size 65 to permit its use as a reservoir in connection with the circulation of water through the radiator and shaped with an upper part 5 to fit beneath the radiator 1. At the end walls of the tank are provided connecting 70 nipples 6, 6 for the respective branch pipes 7 and 8 attached at the lower part of the radiator to complete the circulation of water through the radiator and the tank by way of these pipes. Preferably the walls of the 75 heating-tank are insulated as at 9 to prevent radiation of heat from the tank and insure heating of the water in the tank as will be described.

Within the tank I provide an interior housing 10, which, as is also the case with the tank, may be made up of metal, or other suitable material. The housing has an end opening 11 in one end wall of the tank, and terminates at its inner end near the opposite end wall of the tank. As shown in the drawings the housing is of flat tubular construction, rectangular in cross section, and properly supported within the lower space of the tank with water surrounding 90 substantially the entire area of the housing, except for its open end 11.

The heating element 12 illustrated particularly in Fig. 5 is of flat rectangular formation and of proper dimensions to slip readily into the housing after its end has been inserted in the opening 11 provided therefor. Electric heating coils 13 are provided for the heating element and at its outer end it is furnished with the usual wires 100 14 and a plug 15. The plug may be inserted in a wall socket as 16 located near the floor as seen in Fig. 1.

It will be apparent that the radiators located in the several rooms of a dwelling 105 may all be equipped with the stationary tank and connections therefrom to the radiator, and that these radiators may be connected in the usual hot-water heating system, or they may be independent units 110 entirely separate one from another. In either event, the portable heating element

is adapted for use with any one of the units. Thus some or all of the units in a system may be equipped with the portable heating element, or one or more of the heating elements may be used in connection with selected units for the purpose of heating desired rooms.

Each of the radiators is of course provided with an adjacent electric socket-plate 10 and socket 16, and the electrical connections are arranged in such manner that the heating elements are interchangeable and may readily be connected and disconnected when required. The housing is located in the water heating tank and the heating element is positioned within the housing in such manner that a maximum amount of heat is radiated through the housing to the water in the tank surrounding the housing, 20 and the heated water in the tank causes a circulation in usual manner through the tank and radiator for the distribution of heat from the radiator. The heating element 12 may be slipped readily into the housing and pushed back into its proper position when it will be entirely concealed, and the only substantial change or alteration in the appearance of the standard radiator is caused by the presence of the

tank 4 which is not obtrusive. By this 30 combination and arrangement of parts a convenient and inexpensive appliance is provided which is quite simple both in construction and in use and may be handled or manipulated by unskilled persons without 35 likelihood of becoming disarranged or inoperative. And as the parts are not complicated, but are readily accessible, they may be maintained in efficient working condition at all times. 40

Having thus fully described my invention, what I claim as new and desire to secure by Letters Patent is—

The combination with a hot water heat-radiator, of a water-heating tank therebeneath 45 and connections at the ends of said tank to said radiator, a housing rectangular in cross section having an open end supported in an end opening in one wall of said tank, said housing located within the tank to provide a surrounding water space and having its inner closed end terminating near the opposite end wall of said tank, and a removable electric heating element in said housing. 50 55

In testimony whereof I affix my signature.

H. PHILIP FLICKINGER.
